BURN GUARD

John F. Reynolds and Fred C. Wilhelm, Minneapolis, Minn., assignors to The Unipress Company, Incorporated, Minneapolis, Minn., a corporation of Minnesota

Application June 4, 1932, Serial No. 615,398

10 Claims. (Cl. 74—614)

This invention relates to improvements in garment presses, and has for its main object to provide automatically operable guard means adapted to be interposed between the pressing surfaces to prevent the hands of an operator from coming in contact with the heated pressing surface of the head while arranging the goods over the buck, and smoothing it out at the rear portion thereof.

10 Features of the invention include the details of construction, along with the broader ideas of means inherent in the disclosure.

Objects, features and advantages of the invention will be set forth in the description of the drawings forming a part of this application, and in said drawings:

Figure 1 is a side view illustrating one embodiment of the present invention as applied to a garment press, with the heat-guard in guarding position;

Figure 2 is a vertical section on line 2—2 of Figure 3, showing the press closed and the guard withdrawn and also showing in dot-and-dash lines the opposite position of the guard; and

25 Figure 3 is a vertical section through the arm, taken on line 3—3 of Figure 2 further illustrating the construction.

In the drawings, the numeral 1 generally indicates the frame of a garment press. The press has a "buck" or table 2, a heatable (hollow) pressing head 3, and a rocker or pressing head arm 4. The arm is pivoted as at 5, to the rear column 6. The operating mechanism for the press has not been illustrated, inasmuch as the essential part of this invention relates to the guard feature. It will, of course, be understood that the invention is not limited in its application to any particular make of press, but may be used on any press in which it is desired to prevent the hands of the operator from coming in contact with a heated pressing surface, when the press is open and during introduction and arrangement of the material to be pressed.

The presser head arm in this instance is a frame-like structure including two elements 10 divergent from the rear toward the front of the press, see Figure 3. The pressing head 3 is suitably bolted to this arm in the usual manner. Also bolted to a cross-connecting reenforcing element 11 of the forward or head end of the arm as at 12, is a bracket 13 extending rearwardly and upwardly and having two spaced bearings 14. Rotatable in these bearings is a shaft 15 having opposite ends projecting beyond the bearings. Non-rotatably pinned as at 16 to re-

spective projecting ends of the shafts are depending arms 17 which are arranged to swing between the head 3, and the rear column 6 and pivot 5, of the rock arm. The lower end of each arm is slotted as at 18. The heat guard is indicated at 19 and is made from any suitable material which will withstand heat. In practice, a hard product made from fiberized wood has been found to give good results.

This guard, see Figure 2, has suitably attached along its rear edge and upon its upper face (as by riveting) a metallic reenforcing element 20 in the form of a metal sheet folded upon itself to provide a two-ply reinforced upstanding portion 21. To this element 20 is attached an angle plate, one arm 22 of which is secured as by riveting to the metal reenforcing element and the guard 19 and the other arm 23 of which engages against the front face of the corresponding arm 17. A headed bolt 24 passes through the plate 20 and slot 18, and a suitable nut 25 clampingly secures the parts. By means of the slots, the guard element can be adjusted vertically to assume the proper relation with respect to the heating surface 3^a of the head 3. The guard extends the full length of the head, and is of a width to cover a sufficient area of the rear portion of the pressing surface 3^a, to prevent the hands of the operator coming in contact with said heated surface.

Means is provided which is automatically operable as the result of arm motion to move the guard away from and into guarding relation with the pressing surface 3^a. The guard is moved to guarding position, as shown in Figure 1, during the opening or retracting motion of the pressing head. Conversely, the guard is withdrawn as the head moves to pressing position.

In order to accomplish this movement automatically, see Figures 2 and 3, an arm 30 is pinned as at 31 to the shaft 15 at a point intermediate the bearings 16, and elements 10. The lower end of this arm is then attached by a two-part link to an upright element 32, also see Figure 3, bolted to the column 6. The parts of the link are adjustable. One part 35 is forked and is connected to the lower end of the arm 30 by pivot 36. This element 35 has a rod 37 threaded therein, the opposite end of the rod being threaded into an element 38 which is pivotally connected to the upright element 32 as at 40. The means by which the arm 30 is connected to a stationary part of the press (32), therefore, includes a part 37 which can be adjusted to vary the degree of swing of the arms 17 and, therefore, of the guard. This adjustment, along with the adjustment of

- the brackets or angles of the guard 19, provides means for obtaining accurate positional relation between the guard and the working face of the head 3.
5. An inspection of Figure 1 shows that when the press is open, the rear edges of the buck, and pressing head, are comparatively closely spaced, and that these elements are angularly related and divergent in a direction toward the operator.
10. Because of the comparatively closely spaced relation of the rear edges of the buck and head under the conditions mentioned, the hands of the operator are often burned by coming in contact with the heated surface of the upper head when arranging and smoothing the goods, particularly at the rear side of the buck.
15. The operation will be clear from an inspection of Figures 1 and 2. When the arm moves downwardly from its position shown in full lines in Figure 1, and dot-and-dash lines in Figure 2, the shaft 15 moves along the line A—A, see Figure 2, to lengthen the distance between the pivotal point 40, and the shaft 15. Because of the link and arm connection, the shaft 15 is rotated in 20 anti-clockwise direction and the arms 17 are swung in a corresponding direction to withdraw the guard to the position shown in Figure 2. On reverse motion of the arm, that is on retracting motion, the guard is by reverse process brought 25 again to the position shown in Figure 1.
20. The device, as an attachment, can be applied to various forms of presses without any extended modification of the press structure. A feature is the pivotal mounting of the guard on the arm and the provision of a connection between this 25 guard and a stationary part of the machine. There are certain advantages in attaching the device in this manner, rather than directly to the heated head 3. The arrangement, rearwardly 30 of the head as shown, places the operating parts so that they are less exposed to heat since the only part which lies directly over the chest or head is the rearwardly extending portion of the bracket 13.
35. We claim as our invention:
1. In combination with a pressing machine having a heatable presser head structure, a stiff heat-guard of sheet material and means supporting it on the head structure to swing into guarding position with the pressing face of the head, means by which the guard can be adjusted upon its swinging support to vary its spaced relation with reference to the face of the heated face of the head, and means automatically operable 40 as the result of head motion to move the guard away from and into guarding position, including a part which can be adjusted to vary the degree of swing of the guard support.
  2. In combination with a pressing machine 45 having an arm having a heatable pressing head, a stiff heat guard of sheet material and means swingingly pivoting it to the arm so that it can be swung forwardly from a position spaced from the rear of the head into guarding position with the pressing face of the head, and means automatically operable as a result of arm motion 50 to move the guard into and away from guarding position respectively as the presser head is retracted and advanced.
  3. An ironing press comprising a frame and a pivoted arm having a heatable pressing head, a heat guard and means swingingly mounting said guard including a part pivoted to the arm at the rear of and above the head and adapting said 55 guard to be opposed to and to swing toward and away from the longitudinal rear edge of the head, to bring the guard into heat guarding relation with the heated pressing face of the head, and means for automatically moving the guard to guarding position when the arm is retracted, and vice versa. 60
  4. An ironing press comprising a frame and a pivoted heatable pressing head, a shaft which is journaled in and movable with the head, a stiff heat guard of sheet material and means attaching it to the shaft for movement therewith, an arm on said shaft and means connecting the arm with a stationary part of the press to operate the shaft to swing the guard to guarding position when the press arm is retracted and vice versa. 65
  5. An ironing press comprising a frame and a pivoted heatable pressing head, a heat guard, a shaft movable with the head, means attaching the guard to the shaft for motion therewith, said guard being arranged between the frame and the rear of the head, an arm on said shaft, and means connecting the arm with a stationary part of the press to operate the shaft to swing the guard to guarding position when the press arm is retracted and vice versa. 70
  6. An ironing press comprising a frame and a pivoted pressing arm having a heatable pressing head, a heat guard means including a part mounted on a shaft rotatably journaled on the arm, a heat guard element carried by the part, an arm on said shaft, and a link connecting the arm with a stationary part of the press to rotate the shaft to swing the guard to guarding position when the press arm is retracted and vice versa. 75
  7. An ironing press comprising a frame and a pivoted pressing arm having a heatable pressing head, heat guard means including a part mounted on a shaft journaled on the arm, a bracket attached to the part, a heat guard element attached to the bracket, an arm on said shaft, and means connecting the arm with a stationary part of the press to operate the shaft to swing the guard to guarding position when the press arm is retracted, and vice versa. 80
  8. An ironing press comprising a frame and a pivoted pressing head arm having a heatable pressing head, a shaft journaled on the arm and parallel with the pivotal axis of the arm, heat guard means including a part mounted on said shaft, said part extending downwardly to oscillate between said axis and the rear of the head, a bracket attached to said part, means for adjusting the bracket lengthwise of the part, a stiff heat guard element attached to the bracket, 85 an arm on said shaft, a link connecting the arm with a stationary part of the press to operate the shaft to swing the guard to guarding position when the pressing arm is retracted and vice versa. 90
  9. An ironing press comprising a frame and a pivoted pressing head arm having a heatable pressing head, a shaft journaled on the arm and parallel with the pivotal axis of the arm, heat guard means including a part mounted on said shaft, said arm extending downwardly to oscillate between said axis and the rear of the head, a bracket attached to said part, means for adjusting the bracket lengthwise of the part, a heat guard element of fiberized wood attached 95 to the bracket and of an area sufficient to cover the rear portion of the pressing face of the head throughout its length, an arm on said shaft, a link connecting the arm with a stationary part of the press to operate the shaft to swing the 100

guard to guarding position when the pressing arm is retracted and vice versa, and means for adjusting the length of the link.

10. In combination with a pressing machine having two pressing elements cooperable for a pressing operation, one being heatable and having an arm for moving it toward and away from the other, a sheet of non heat conducting material and means attaching it to the arm to 10 swing from a point rearwardly of and in a di-

rection toward the rear of said elements to guarding position between the pressing elements and in close position to the pressing surface of the movable element, and means automatically operable as a result of arm motion to move the guard toward and away from guarding position respectively as the press opens and closes. 5
